UNITED STATES PATENT OFFICE.

THURE E. DAHL, OF NEW YORK, N. Y.

DESIGN FOR AN ELECTRIC FIXTURE.

• 60,896.

Specification for Design.

Patented Apr. 25, 1922.

Application filed May 31, 1921. Serial No. 473,920. Term of patent 3½ years.

To all whom it may concern:

Be it known that I, THURE E. DAHL, a subject of the King of Sweden, residing at New York, in the county of New York and State of New York, in the United States of America, have invented a new, original, and ornamental Design for an Electric Fixture, of which the following is a specification, refer-

ence being had to the accompanying drawing, forming part thereof.

The figure is a perspective view of an electric fixture, showing my new design.

I claim:

The ornamental design for an electric fixture, as shown.

THURE E. DAHL.
